US00D892127S

(12) **United States Design Patent** (10) Patent No.: **US D892,127 S**
Chen (45) Date of Patent: ** Aug. 4, 2020

(54) **ROTATING KEYBOARD CASE WITH KEYBOARD**

(71) Applicant: **HaiWen Chen**, Guangdong (CN)

(72) Inventor: **HaiWen Chen**, Guangdong (CN)

(**) Term: **15 Years**

(21) Appl. No.: **29/687,287**

(22) Filed: **Apr. 11, 2019**

(51) LOC (12) Cl. **14-02**

(52) U.S. Cl.

USPC **D14/440**; D14/316

(58) **Field of Classification Search**

USPC D14/440, 447, 250, 316; 206/45.23, 320, 206/45.2; 361/679.55; 294/25; 224/218

CLAIM

I claim the ornamental design for the rotating keyboard case with keyboard, as shown and described.

DESCRIPTION

FIG. 1 is a perspective view of a rotating keyboard case with keyboard showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof.

1 Claim, 8 Drawing Sheets
